GLUING MEANS FOR PACKAGING
MACHINERY

Alfred German Rose, Gainsborough, England, assignor to Rose Brothers (Gainsborough) Limited, Gainsborough, England, a British company

Application April 30, 1942, Serial No. 441,139
In Great Britain February 7, 1941

6 Claims. (Cl. 91—50)

This invention relates to packaging machinery and more particularly to apparatus for closing and sealing fibre or cardboard boxes or like containers (hereinafter referred to as "containers") of the type comprising a tubular body portion and end portions formed by first folding extensions of two opposed sides of the body portion (hereinafter referred to as "inside flaps") at right angles to the sides of the body portion and then completing the end portions by folding the remaining extensions (hereinafter referred to as "outside flaps") on to the inside flaps.

The invention is particularly concerned with the type of apparatus in which containers are fed to a flap-folding and gluing device which operates first to fold inwardly the inside flaps and then to fold outwardly the outside flaps in preparation for the application of glue. In this type of apparatus (hereinafter referred to as the "type described"), it is usual to provide for adjustment of the apparatus to accommodate containers of various sizes. When dealing with containers in which the inside flaps when folded are separated by a gap exposing the contents of the container, it is very desirable that the film of glue applied to the outside flaps should not extend over the full length of the flaps in order to avoid the portion of the outside flaps extending over the gap between the inside flaps being stuck to the contents of the containers. To this end, therefore, the gluing device is so arranged that, during the passage of the outside flaps through the gluing device, the glue-applying roller is moved clear of the flaps, by means of a rotating cam operating in timed relation to the movement of the container through the gluing device, so as to allow the portions of the outside flaps corresponding to the gap between the inside flaps to pass through the gluing device without making contact with the glue-applying roller. The gluing device is arranged to be adjusted automatically when the apparatus is adjusted to accommodate containers of different width. In this apparatus, however, the portion of the outside flaps to which no glue is applied is of a fixed length depending on the profile of the cam.

As mentioned above, the apparatus is adjustable to accommodate containers of various sizes and it is found convenient to determine at the outset the range of sizes of container that the apparatus is to accommodate and to set the machine accordingly. Thus, considering the range of containers in relation to their width, the smallest container may be of considerable length in relation to its width whereas the next larger

5 container may differ from the smaller container only to a small degree as regards the width but may be much shorter in length. Again, the length of the inside flaps, which of course determines the gap between the flaps and, therefore, the length of the portion of the outside flap on which no glue must be applied, may vary considerably over the whole range of containers. Whilst, therefore, the gluing device as a whole 10 is adjustable to accommodate containers of different width and of different height, no provision is made for varying the length of the portion of the outside flap on which no glue is to be applied.

15 15 It is an object of the present invention, therefore, to provide an apparatus of the type described in which, for a given range of sizes of container, the gluing device is adjusted for a given size of container, as regards the length 20 of the portion of the outside flaps on which no glue is to be applied, automatically with the adjustment of the apparatus to accommodate the width of that container.

According to the present invention, therefore, 25 25 there is provided an apparatus of the type described wherein the gluing device is provided with a rotatable cam member consisting of a plurality of cam surfaces arranged on a common support in such a manner that as the apparatus 30 is adjusted to accommodate the width of a given container the cam surface appropriate to that container becomes operative.

Usually, in the type of apparatus with which 35 35 the present invention is concerned, the upper and lower outside flaps of the containers are glued at the same time, there being one gluing device for each outside flap. It will be understood that, in such a case, each gluing device is controlled according to the invention, by a rotatable cam 40 consisting of a plurality of cam surfaces as described above so that if the container to be operated upon is of the type in which the outside flaps are together equal in area to the end of the container and abut in the end of the container, a portion of each outside flap, corresponding in length to the gap between the inside flaps, can be left without glue by suitably designing the cam surface appropriate to that container in each gluing device; or, if the container is of the type in which the outside flaps are each 45 equal in area to the end of the container and are arranged to overlap on the end of the container, the inner of the outside flaps at each end of the container may be left without glue on the portion corresponding to the gap between

the inside flaps in the manner described above, while the outer of the outside flaps at each end of the container may be glued all over so as to form a good seal by substituting cylindrical surfaces for the corresponding cam surfaces. Again, if any container within the range is of the type in which the inside flaps are together equal in area to the end of the container and arranged to abut in the end of the container, and there is thus no necessity to leave a portion of the outside flaps free of glue, the corresponding cam surfaces in each case may be replaced by cylindrical surfaces.

It will thus be seen that, by the use of the present invention, the apparatus can be set to perform the requisite operations on a range of containers of different dimensions, different settings for different containers being brought about merely by the adjustment of the apparatus to accommodate the width of the containers.

By way of example, the invention will now be described in greater detail with reference to the accompanying diagrammatic drawings, in which:

Figure 1 is an elevation of part of an apparatus for closing and sealing containers, constructed in accordance with this invention.

Figure 2 is an elevation of a part of the apparatus shown in Figure 1, drawn to a somewhat larger scale, certain parts being removed for clarity of illustration.

Figure 3 is a plan view of the same part of the apparatus as that shown in Figure 2.

Figure 4 is a sectional elevation, taken on the line 4—4 of Figure 2.

Figure 5 is an elevation, drawn to a somewhat larger scale, of another part of the apparatus shown in Figure 1.

Figure 6 is a plan view of the apparatus shown in Figure 5 with the addition of framework and drive mechanism.

Figure 7 is a front view of the apparatus shown in Figures 5 and 6, viewed in the direction of the arrow in Figure 6.

Figure 8 is a view similar to Figure 4, showing the apparatus in a different position of lateral adjustment, and

Figure 9 is a view similar to Figure 7, showing the apparatus in a different position of lateral adjustment.

Referring to Figure 1, containers 11 are fed through the apparatus by means of pusher bars 12 carried by a pair of chains 13 which are driven through chain and sprocket gearing 14 from a combined reduction gear and motor 16. During the passage of the containers 11 through the apparatus, they first pass through a folding device generally indicated by reference numeral 17, which in this case is of the type described in British Patent Specification No. 536,069, which folds inwardly the upper inside flaps 18 (the lower inside flaps having been previously folded inwardly), then through ploughs 19 which plough the outside flaps 21 of the container outwardly so that they lie in horizontal planes, then through pairs of upper and lower gluing devices generally indicated by reference numerals 22 and 23 respectively, which apply a film of glue to the inside surface of the outside flaps, and then through further ploughs 24 which plough the glued flaps over into closed position.

The apparatus is adjustable as regards the width of the container and its height so as to be capable of accommodating containers of various sizes, and the general construction and operation of this type of apparatus is described in British

Patent Specification No. 541,421, so that it is only necessary to describe in detail those parts of the apparatus with which the present invention is particularly concerned. Reference may be made to the above-mentioned Specification No. 541,421 for further details of the general construction and operation of the apparatus as a whole.

10 The upper gluing devices 22 are substantially identical in construction and are each carried by a bracket 26 slidably mounted on a pair of shafts 27 carried by a pair of brackets 28, and their lateral adjustment is brought about by means of a rotatable screwed shaft 29 mounted in the brackets 26 and engaging the bracket 26, the screwed shaft 29 being driven by chain and sprocket gearing 31 from a similar screwed shaft 32 which, in turn, is driven through suitable gearing from a motor 33. The brackets 26 are 15 slidably mounted on pairs of pillars 34 and are vertically adjustable by means of screws 35 which are driven through suitable gearing from a motor 33.

As mentioned above, the gluing devices 22 are 20 substantially identical in construction, and the construction and operation of one of the gluing devices 22 will now be described with particular reference to Figures 2, 3 and 4. Mounted in bearings 36 and 38 is a glue roller shaft 41 to which 25 is attached a glue roller 42 arranged to dip into a glue bath 43, the bearing 38 being formed in a bracket 44 depending from the bracket 26 and the bearing 36 in a downward extension of the bracket 26. The glue bath 43 is supported by 30 a pair of platforms 46 extending respectively from the depending bracket 44 and a further bracket 47 also depending from the bracket 26. Freely mounted on the glue roller shaft 41 is a pair of frames 48 arranged to carry rotatable shafts 49 and 51 to which is secured respectively a transfer roller 52 and a glue-applying roller 53. The 35 shafts 49 and 51 are driven from the shaft 41 through a pair of gears 54 and 56 secured respectively to the shafts 41 and 49 and a further pair of gears 57 and 58 secured respectively to the shafts 49 and 51, an intermediate gear 59 being provided between each pair of gears 54, 56 and 57, 58, the intermediate gears 59 being freely mounted on the frames 48. The shaft 41 is 40 driven from a shaft 61 slidably mounted in bearings 62 and 63, depending respectively from the bracket 26 and the bracket 47, by means of a gear 64 attached to the shaft 61 and engaging the gear 54. The shaft 61 is driven through a 45 pair of spiral gears 66 and 67, the gear 66 being slidably mounted on the shaft 61 and provided with a feather key while the gear 67 is secured to a vertical shaft 68. The shaft 68, in turn, is 50 driven by a further pair of spiral gears 69 and 71, the gear 69 being mounted on a shaft 72 carried in a pair of bearings 73 in the main frames 74 of the machine, and the shaft 72 being driven 55 by chain and sprocket gearing 76 from the motor 16. The gear 69 is secured to a bearing sleeve 77 rotatably mounted in brackets 78 and 79, attached to the main frames 74. The shaft 68 is 60 supported at its upper end in a bearing 81 and at its lower end in the bearing sleeve 77 by which it is driven by means of a feather key and which allows for the vertical movement of the shaft 68 during the adjustment of the apparatus for containers of different height.

Mounted in a bearing 81 carried by a pair of brackets 82 attached to the bracket 26 is a cam shaft 83 which is driven from the shaft 61 by a 65

pair of gears 94 and 95, the gear 94 being slidably mounted on the shaft 81 and provided with a feather key, and the gear 95 being secured to the shaft 93. Secured to the shaft 93 is a cam member 96 arranged to co-operate with a cam roller 97 mounted on the shaft 81. The cam member 96 is provided with a number of cam surfaces 98 each of which becomes operative as the apparatus is adjusted to accommodate the width of the container appropriate to that cam surface.

It will thus be seen that the whole of the gluing device is adjusted bodily in a vertical direction, by reason of its attachment to the bracket 28, as that bracket is adjusted to accommodate containers of different height, the drive from the motor 16 continuing to operate due to the slideable mounting of the shaft 88 in the sleeve 77. During the adjustment of the apparatus to accommodate containers of different width, it will be seen that, as the bracket 28 is moved laterally, by rotation of the screwed shaft 29, the bracket 28 will cause the gluing device to move bodily in one direction or the other according as the apparatus is being adjusted to accommodate a narrower or wider container, and it will be seen that during this movement the cam roller 97 will move from the cam surface 98 for the time being in operation to the cam surface 98 appropriate to the new container to be accommodated, and since the shaft 81 is slidably mounted and moves bodily with the gluing device, it is necessary to prevent the gear 94 from moving with it. Accordingly, the gears 94 and 86 which, as described above, are slidably mounted on the shaft 81, are retained in position on the shaft 81 by means of a pin 99 depending from a retaining plate 101 attached to the bracket 28, the pin 99 engaging a groove in the boss of the gear 94.

The length of each of the cam surfaces 98 and its circumferential disposition are designed to suit a particular container, and the timing of the cam shaft 93 in relation to the conveyor chain 13 is such that the cam surface 98 for the time being in operation will cause the glue-applying roller 53 to be lifted out of contact with the outside flaps of the container during the passage of a portion of the outside flaps, corresponding to the gap between the inside flaps, past the glue-applying roller.

The lower gluing devices 23, like the devices 22, are identical in construction and are arranged for lateral adjustment in a similar manner to the gluing devices 22, the gluing device generally being slidably mounted on a guide shaft 102 secured to the frames 14, the lateral movement being brought about by a screwed shaft 103 driven, like the screwed shafts 29 and 32, through suitable gearing from the motor 33, the screwed shaft 103 engaging a frame 105 of the gluing device. As shown in Figure 5, the lower gluing devices differ from the upper ones in that a glue-applying roller 104 is mounted directly in a glue bath 106 and supported in bearings 107 carried by a frame 108 freely mounted on the guide shaft 102. The drive to the glue-applying roller 104 is from the shaft 72 by a pair of gears 109 and 111, the gear 111 being freely mounted on a blank portion of the screwed shaft 103, and further gears 114, 116 and 117, the gear 114 being attached to the gear 111.

The lower gluing device is provided with a cam member 118, similar to the cam member 96, and similarly provided with a number of cam surfaces 119, arranged to co-operate with a cam roller 121

freely mounted on the frame 108, and since the glue-applying roller 104, in this case, has to fall away from the flaps, the cam surfaces 119 are in the form of depressions in the cam member 118.

As in the case of the cam surfaces 98, each cam surface 119 is designed and positioned on the cam member 118 for a particular size of container, and the cam member 118 is mounted on the shaft 72 and timed in relation to the conveyor chain 13 in a similar manner to the timing of the cam shaft 93.

In order to maintain the drive to the glue-applying roller 104 during the pivotal movement of the frame 108 as the cam roller 121 drops on to the cam surface 119, the gear 116 is mounted on a stud 122 arranged to slide in a slot 123 in the frame 108, the stud 122 being connected with the shaft 103 by means of a link 124.

It will thus be seen that once the range of sizes of container has been determined and the cam surfaces 98 and 119 designed accordingly, the setting of the gluing devices to suit any container within the range is effected automatically as the apparatus is adjusted to accommodate the width of that container. The invention is particularly useful, therefore, in the above type of packaging apparatus where the adjustment of the apparatus for the accommodation of containers of different height and width is brought about by the central controlling apparatus described in the above-mentioned Specification No. 541,421.

I claim:

1. Apparatus of the type described including a support, a bracket mounted on said support for lateral movement with respect thereto, a gluing roller having up and down movement on said bracket, a rotary cam member carried by said support, a cam roller connected with said gluing roller, said cam member having a plurality of cam surfaces with each of which said cam roller cooperates according to the lateral adjustment of said cam roller to elevate the gluing roller to vary the time the latter remains out of glue-applying position, and means to cause the lateral movement of said bracket so as to cause a corresponding lateral adjustment of said cam roller.

2. Apparatus of the type described, comprising a support, a bracket mounted on said support for lateral movement with respect thereto, a gluing roller mounted on said bracket for movement in up and down directions, a cam member rotatably mounted on said support and arranged periodically to engage means laterally movable with said gluing roller for causing said gluing roller to move out of glue-applying position in timed relation to the movement of the containers past said gluing roller, and means for adjusting said bracket laterally to vary the lateral position of said gluing roller to suit containers of different width, said cam member having a plurality of cam surfaces, each appropriate to a given size of container, each cam surface co-operating with said means for moving said gluing roller out of glue-applying position, according to the lateral adjustment of said gluing roller to suit the width of said size of container, to move said gluing roller out of glue-applying position for a time appropriate to that container.

3. Apparatus of the type described, comprising a support, a bracket mounted on said support for lateral movement with respect thereto, a gluing roller mounted on said bracket for movement in up and down directions, a cam member rotatably mounted on said support and arranged periodically to engage means, laterally movable with said

gluing roller, for causing said gluing roller to move out of glue-applying position in timed relation to the movement of the containers past said gluing roller, and means for adjusting said bracket laterally to vary the lateral position of said gluing roller to suit containers of different width, said cam member having a plurality of cam surfaces formed integrally therewith, each cam surface co-operating with said means for moving said gluing roller out of glue-applying position, according to the lateral adjustment of said gluing roller to suit the width of said size of container, to move said gluing roller out of glue-applying position for a time appropriate to that container.

4. Apparatus of the type described, comprising a support, a bracket mounted on said support for lateral movement with respect thereto, a gluing roller mounted on said bracket for movement in up and down directions, a cam roller freely mounted on said bracket, a cam member rotatably mounted on said support and arranged periodically to engage said cam roller and by such engagement cause said gluing roller to move out of glue-applying position in timed relation to the movement of the containers past said gluing roller, and means for adjusting said bracket laterally to vary the lateral position of said gluing roller to suit containers of different width, said cam member having a plurality of cam surfaces, each appropriate to a given size of container, each cam surface co-operating with said cam roller, according to the lateral adjustment of said gluing roller to suit the width of said size of container, to move said gluing roller out of glue-applying position for a time appropriate to that container.

5. In a packaging apparatus of the type de-

- scribed, a support, a bracket mounted on said support for lateral movement with respect thereto, a gluing roller mounted on said bracket for movement in up and down directions, a cam member rotatably mounted on said support and arranged periodically to engage means, laterally movable with said gluing roller, for causing said gluing roller to move out of glue-applying position in timed relation to the movement of the containers past said gluing roller, and means for adjusting said bracket laterally to vary the lateral position of said gluing roller to suit containers of different width, said cam member having a plurality of cam surfaces, each appropriate to a given size of container, each cam surface co-operating with said means for moving said gluing roller out of glue-applying position, according to the lateral adjustment of said gluing roller to suit the width of said size of container, to raise said gluing roller out of glue-applying position for a time appropriate to that container.
6. Apparatus of the type described including a vertically adjustable support, means operable to effect the vertical adjustment of the support, a bracket mounted on said support for lateral movement with respect thereto, a gluing roller having up and down movement on said bracket, a rotary cam member carried by said support, a cam roller connected with said gluing roller, said cam member having a plurality of cam surfaces with each of which said cam roller cooperates according to the lateral adjustment of said cam roller to elevate the gluing roller to vary the time the latter remains out of glue-applying position, and means to cause the lateral movement of said bracket so as to cause a corresponding lateral adjustment of said cam roller.

ALFRED GERMAN ROSE.
